UNITED STATES PATENT OFFICE.

REYNOLD JANNEY, OF NEW YORK, N. Y., ASSIGNOR TO THE WATERBURY TOOL COMPANY, OF NEW BRITAIN, CONNECTICUT, A CORPORATION OF CONNECTICUT.

CONTROLLING APPARATUS FOR HYDRAULIC VARIABLE-SPEED GEARS.

1,108,443.

Specification of Letters Patent. Patented Aug. 25, 1914.

Application filed March 17, 1914. Serial No. 825,252.

To all whom it may concern:

Be it known that I, REYNOLD JANNEY, a citizen of the United States, residing at New York, in the county of New York and State of New York, have invented certain new and useful Improvements in Controlling Apparatus for Hydraulic Variable-Speed Gears, of which the following is a specification.

10. This invention relates to controlling-apparatus for hydraulic-variable-speed gears, the object of the invention being to provide simple and effective means which is positive and certain in action and by which the 15 transmission of power can be effectively governed to either stop or start a driven member or to effect variations in speed of said driven member of whatever character the same may be.

20. In the drawings accompanying and forming part of the present specification I have shown in detail one of the convenient forms of embodiment of the invention which to enable those skilled in the art to practise 25 the same will be set forth fully in the following description. I do not restrict myself to this showing; I may depart therefrom in several respects within the scope of the invention defined by the claims following said 30 description.

Referring to said drawings: Figure 1 is a sectional side elevation of controlling apparatus embodying my invention and showing the same operatively connected with a 35 hydraulic-variable-speed gear of known construction. Fig. 2 is a horizontal sectional detail, the section being taken through the lower end of the control shaft and illustrating particularly the connection between said 40 control shaft and the regulator.

Like characters refer to like parts in both figures of the drawings.

As will hereinafter appear my controlling apparatus operates usually in conjunction 45 with a regulator which is shifted to obtain different relations in a hydraulic variable speed gear. This regulator may vary decidedly as to type. It may as shown, although this is always not necessary, consist 50 of what is known in a hydraulic-variable-speed gear as a "tilting-box."

A hydraulic-variable-speed-gear usually 55 comprises a pump section or end and a hydraulic-engine section or end, and it has been the practice to relate these two sections

or ends in a great many different ways, which are unnecessary for me to describe as my invention is not founded thereon. In Fig. 1 of the drawings, however, I have illustrated one hydraulic-variable-speed gear 60 of known construction which is practically similar to that shown in Letters Patent No. 924,787 granted to me June 15, 1909, and to which reference may be had. In said view the numeral 2 denotes the pump end 65 or section, while the numeral 3 is applied to the hydraulic engine or motor section thereof. Within the casing of the pump end 2 is mounted the tilting-box 4 which as already observed, presents a suitable regulator. This tilting-box 4 is shown as occupying its neutral position in Fig. 1. When said tilting box is moved in one direction from its neutral position a shaft as 5 constituting a suitable driven member, will be rotated in 70 one direction, the speed of said shaft being increased progressively as the tilting box moves from said neutral position. When the tilting box is oppositely moved the same increase of speed follows, but the shaft 5 is 75 driven oppositely. Supported by the pump or A-end 2 is the shaft 6 which is usually continuously driven, for instance by an electric-motor.

To shift the tilting-box 4 I have shown 80 the control-shaft 7 which has a suitable operative connection with said tilting-box. That shown and now to be described meets the desired conditions. The lower end of said rotary control shaft 7 extends freely 85 through the block 8 mounted between the branches of the outwardly extending fork 9 of said tilting-box, said block having laterally extending trunnions 10 which are mounted to relatively turn in slides 11 supported 90 for back and forth movement in the longitudinal slots or ways 12 of the branches or fork 9. The lower end of the control shaft may as shown be provided with a nut 13 between which and the block or sleeve 8 is 95 interposed the washer 14. The shaft 7 where it extends through the block or sleeve 8 is reduced so as to present a shoulder 15 to engage the upper surface of the block or sleeve 8, said shoulder and nut presenting 100 jointly a convenient means for preventing longitudinal movement of the shaft 7 with respect to the block or sleeve. When the shaft 7, therefore, is endwise moved, for example upwardly as shown, the tilting box 105

55 60 65 70 75 80 85 90 95 100 105 110

4 is moved in one direction from its neutral position, and when said shaft oppositely moves, said tilting box is moved in an opposite direction from said neutral position.

5 The means whereby this longitudinal movement of the shaft is accomplished will be hereinafter set forth.

It is desirable that lateral movement of the said control shaft should be prevented, 10 and various means may be provided for securing this function, although those shown and now to be described answer satisfactorily. Pivotaly connected with the outer extended ends of the trunnions 10 are blocks

15 16 which in the present case are adapted to slide vertically in ways consisting for example of grooves 17 in the casing of the A-end 2, said casing constituting a part of the framework. It will be clear that the 20 blocks 16 as shown move strictly in a vertical direction or in the direction of the axis of rotation of the rotary control shaft 7, so that they effectually prevent lateral movement of said shaft without interfering with 25 the longitudinal movement thereof.

Any suitable means may be provided for rotating the control shaft. For this purpose said shaft is shown having keyed thereto the band wheel 18 by which said shaft can be 30 directly rotated and about which may be passed one or more times, the cable 19. It, therefore, follows that when the wheel 18 is rotated the shaft 7 will be correspondingly operated. Said shaft projects into the cas- 35

ing of the A-end through a stuffing box as 20. The control shaft 7 is shown provided at its upper end with a screw or threaded portion 21 which extends through and has a threaded connection with a suitable power- 40

transmitting element which as shown consists of the bevel gear 22 mounted in the boxing 23 and held against movement in the direction of the axis of rotation of said shaft 7, by said boxing supported by brackets or 45

uprights 24 and 25 rising from the casing of the A-end 2. In mesh with the bevel gear 22 and also inclosed by the boxing 23 is the bevel gear 26 at the inner end of the shaft 27 supported by the bracket 25, said 50

shaft 27 being operatively connected in some desirable manner as by the train of gears 28 with the driven shaft 5 which driven shaft as will be understood is caused to rotate when the tilting box 5 is moved in either 55

direction from its neutral position. It will be assumed that the shaft 7 is rotated by the hand wheel 18. On the rotation of said shaft it is moved longitudinally by the bevel gear 22 acting as a feed nut, to shift the 60 tilting box 4 from its neutral position. When said tilting box is thus operated the shaft 5 is caused to rotate and through the described gearing, to rotate the shaft 27, so that through the train of gears 28 and shaft 65 27, the bevel gear 26 will be rotated, where-

by the latter will rotate the gear 22 and thereby tend to move the shaft 7 in an endwise direction opposite to that in which the shaft 7 is initially endwise moved, so that the engine or B-end 3 through instrumentalities such as described, tends when in action to longitudinally move the shaft 7 in a direction opposite to that in which said shaft is longitudinally moved by its controlling member of whatever form the same 75 may be, by reason of which variations in speed of the shaft 5 in either direction can be obtained.

Suitable means is provided for taking up wear between the bevel gear or feed nut 22, and the feed screw 21, and like the other features of the invention, said means may vary in certain particulars, although that shown and now to be described is satisfactory. Fitted to the threaded or screw portion 21 is a nut 30, the threads of the interior threaded portion of said nut corresponding with those of the threaded portion 21, so that by turning said nut, the shaft 7 can be moved endwise to bring the threaded portion 21 solidly against the interior threads of the bevel gear 22 and eliminate any backlash that may be present. As shown the nut 30 has external threads to engage corresponding threads in the socket 31 of the 95 bevel gear 22 in which said nut 30 fits, so that by turning the nut in the proper direction, it can be fed inward or outward to effect corresponding movements of the threaded portion 21. The external threads 100 31 are of very fine pitch and any motion therefore, that is given by said nut 30 to the threaded portion 21 will be comparatively slight, being just sufficient to compensate for any wear that may occur between 105 said threaded portion 21 and the threaded portion of the bevel gear 22. The motion therefore, is very small indeed and is not enough to move the tilting box 4 from its neutral position an extent sufficient to start 110 the shaft 5. Any desirable means may be provided for holding the nut 30 in its adjusted position, the screws 32 being shown for this purpose and being tapped through the nut and their tips being adapted to engage the upper surface of the bevel gear 22. The nut 30 and the upper threaded end of the shaft 7 can be received by the cap-piece 33 having as shown a threaded connection with the casing or boxing 23. 115

What I claim is:

1. The combination of a hydraulic variable speed gear involving a regulator, a rotary control shaft connected with said regulator, a power transferring member having 125 a threaded connection with said shaft, the latter when rotated being longitudinally movable in one direction by said threaded connection to thereby shift the regulator, and means operable by the hydraulic vari- 130

able speed gear, for turning said power-transferring member to move said shaft endwise in the opposite direction.

2. The combination of a hydraulic variable speed gear involving a regulator, a rotary control shaft connected with said regulator, a power transferring member having a threaded connection with said shaft, the latter when rotated being longitudinally movable in one direction by said threaded connection to thereby shift the regulator, means operable by the hydraulic variable speed gear, for turning said power transferring member to move said shaft endwise in the opposite direction, and means for compensating for wear between said shaft and said power transferring member.

3. The combination of a hydraulic variable speed gear involving a regulator, a rotary shaft connected with said regulator and having a threaded portion thereon, a rotary member constituting a nut interiorly threaded to receive the threaded portion of said shaft, whereby when the shaft is rotated it will be moved in one direction by said rotary member to thereby shift the regulator, means operable by the hydraulic variable speed gear, for automatically turning said rotary member to thereby cause the movement of said shaft endwise in the opposite direction, means for preventing movement of said rotary member in the direction of its axis of movement, and means for relatively operating said shaft and rotary member to take up wear between the threaded portions of the shaft and the rotary member.

4. The combination of a hydraulic variable speed gear involving a regulator, a rotary shaft connected with said regulator and having a threaded portion thereon, a rotary member constituting a nut interiorly threaded to receive the threaded portion of said

shaft, whereby when the shaft is rotated it will be moved in one direction by said rotary member to thereby shift the regulator, means operable by the hydraulic variable speed gear, for automatically turning said rotary member to thereby cause the movement of said shaft endwise in the opposite direction, means for preventing movement of said rotary member in the direction of its axis of movement, and a nut having a threaded connection with the threaded portion of said shaft and also having a threaded connection with said rotary member.

5. The combination of a hydraulic variable speed gear involving a regulator, a rotary shaft connected with said regulator and having a threaded portion thereon, a rotary member constituting a nut interiorly threaded to receive the threaded portion of said shaft, whereby when the shaft is rotated it will be moved in one direction by said rotary member to thereby shift the regulator, means operable by the hydraulic variable speed gear, for automatically turning said rotary member to thereby cause the movement of said shaft endwise in the opposite direction, means for preventing movement of said rotary member in the direction of its axis of movement, a nut having a threaded connection with the threaded portion of said shaft and also having a threaded connection with said rotary member, and screws tapped through the nut and engaging said rotary member for adjusting said nut and for holding the same in an adjusted relation.

In testimony whereof I affix my signature in presence of two witnesses.

REYNOLD JANNEY.
